Primary Examiner — Robert M. Spear*Assistant Examiner* — Kendra Leslie Hamilton(74) *Attorney, Agent, or Firm* — J.A. Lindeman & Co., PLLC(57) **CLAIM**

The ornamental design for a pitcher lid, as shown and described.

DESCRIPTION

FIG. 1 is a front and right side perspective view of a pitcher lid in accordance with my new design;

FIG. 2 is a front view of the pitcher lid of FIG. 1;

FIG. 3 is a rear view of the pitcher lid of FIG. 1;

FIG. 4 is a left side view of the pitcher lid of FIG. 1;

FIG. 5 is a right side view of the pitcher lid of FIG. 1;

FIG. 6 is a top view of the pitcher lid of FIG. 1;

FIG. 7 is a bottom view of the pitcher lid of FIG. 1;

FIG. 8 is an assembled right side perspective view thereof, shown in condition of use; and,

FIG. 9 is an exploded right side perspective view with disclaimed rear lid and pitcher shown separated from the claimed lid.

The features shown in broken lines in the drawings represent unclaimed environmental subject matter and form no part of the claimed design.
